UNITED STATES PATENT OFFICE.

ALFRED JUNOD, OF STE. CROIX, VAUD, SWITZERLAND, ASSIGNOR TO M. J. PAILLARD & CO., OF NEW YORK, N. Y.

DUPLEX MUSIC-BOX.

SPECIFICATION forming part of Letters Patent No. 356,251, dated January 18, 1887.

Application filed January 8, 1886. Serial No. 187,950. (No model.)

To all whom it may concern:

Be it known that I, ALFRED JUNOD, of Ste. Croix, Canton of Vaud, in the Republic of Switzerland, have invented a new and Improved Duplex Music-Box, of which the following is a full, clear, and exact description.

The object of my invention is to provide a new and improved musical box which is so constructed that the same melody can be played by two independent cylinders on two independent combs, or a melody can be played by one cylinder on one comb and the accompaniment by the other and independent cylinder on the other comb, or that each cylinder can play a melody alone, the other cylinder and comb being out of operation—that is, removed from the box.

The invention consists in a music-box provided with two independent cylinders and two independent combs or groups of combs, one comb or group of combs being provided for each cylinder, all as will be fully described and set forth hereinafter, and then pointed out in the claims.

Reference is to be had to the accompanying drawings, forming a part of this specification, in which similar letters of reference indicate corresponding parts in all the figures.

Figure 1 is a plan view of my improved music-box, the cover being removed. Fig. 2 is a cross-sectional view of the same on the line xx , Fig. 1. Fig. 3 is a cross-sectional view of the same on the line yy , Fig. 1. Fig. 4 is a longitudinal sectional view of a cylinder mounted on its shaft. Fig. 5 is a detail view of part of the shifting mechanism.

The musical box is provided with the usual base-plate, A, on which the works are secured, and said plate is provided with the two longitudinal slots B B', into which the lower parts of the two pin-cylinders C C' are passed, and at the edges of the said slots the combs D D', or groups of combs, are secured on the base-plate A, one comb or group being provided for each slot.

Each pin-cylinder C or C' is mounted to slide on and turn with a shaft, E, provided at one end with a handle-knob, F, and at the other end with a collar or shoulder, G, between which and the end of the cylinder a spiral

spring, I, surrounds the shaft and presses the cylinder in the direction toward the knob F.

On the end of each shaft E, and beyond the collar G, a disk, J, is mounted, and from the edge of the said disk the handle-piece or wing J' projects, and from the other side of each disk J a pin, K, projects.

The cylinder-bearings L, of which there is one at each end of each slot B B', are provided with the latches M', which are pivoted on the bearings and serve to lock the cylinder-shafts E in the bearings, the said latches being swung over the end parts of the said shafts in the bearings. The cylinders can thus be removed from their bearings and replaced by others when it is desirable to play other melodies.

The interchangeable cylinders are well known and are not to be claimed in this application, and are only described to fully illustrate the character of my improved music-box.

The driving-spring is contained in the drum M, mounted in suitable bearings and provided with the cog-wheel N, which engages with and revolves the pinion O on the shaft P', carrying the cog-wheel R', which engages with and drives the cog-wheel R, mounted on the shaft P, which shafts P and P' are journaled in bearings on the base-plate A, parallel with the same. The shaft P' is also provided with the cog-wheel Q, which drives the flier S.

On the outer surfaces of the wheels R and R' the flat disks T are formed, which are provided in their rims with the notches U for receiving the pins K, projecting from the sides of the disks J, whereby the cylinders are revolved. The driving-spring is wound by means of the lever V in the usual manner or by means of a key.

On one end of the base-plate A the two parallel levers a are pivoted, to swing toward and from each other, and at their inner ends are pressed from each other by the spring d, interposed between them, and between the outer ends of the said levers the wedge-shaped piece g is provided, which is formed on the lower end of a vertically-sliding rod, h, provided at its upper end with the handle-knob m. From the outer edges of the said levers a the arms

p project, which cause the shifting of the cylinders longitudinally on their shafts in the usual manner.

The operation is as follows: When the two cylinders are in the machine or box, they are revolved together and play at the same time, each playing on its own comb, but both being driven from the same spring as their cog-wheels *R* and *R'* engage. The pins on the cylinders can be so arranged that both play the same melody, the two cylinders playing "unisono;" or the pins can be so arranged that one cylinder plays a melody and the other cylinder plays the accompaniment. In case only one cylinder is to play at the time the other cylinder is removed. It is not necessary that the pins of both cylinders act on the teeth of combs, as the pins of one cylinder can act on the ends of levers which operate or play bells, drums, tambourines, or reed instruments, such as are usually employed in large music-boxes. If desired, the cylinders can be so constructed that they cannot be removed from the box. When it is desired to adjust the cylinders in such a manner that they are shifted lengthwise after each revolution, the sliding bar *h* is pushed down, so as to permit the spring *d* to press the ends of the levers *a* from each other, so that the arms *p* can act on the cams on the cylinders in the usual manner. When the cylinders are to be so adjusted that they are not shifted lengthwise after each revolution, the bar *h* is raised, and then the wedge-shaped piece *g* presses the outer ends of the levers *a* from each other, thus preventing the inner ends from being pressed apart by the spring *d*. In some cases it is desirable that the two cylinders shall play one continuous tune, which requires a series of revolutions of each cylinder—that is, the cylinders must be shifted lengthwise while playing said tune. If both cylinders were shifted at the same time, a break would occur in the time, and to avoid this the shifting devices of the cylinders are so arranged that one cylinder is shifted at the time that the other is still playing. For instance, one cylinder plays a melody and is accompanied by the other; but before the first cylinder has completed its revolution the second one is shifted and continues playing, and a short time after the second has been shifted the first completes its revolution and continues playing, and so on, the teeth or pins on the combs being so set that the melody is not interrupted during the time that one cylinder plays alone, and also so arranged that at the time when the two cylinders play together again the teeth of each cylinder will play its proper part of the melody. To play a melody requiring a considerable time, a pin-cylinder having an extraordinarily large diameter is required in ordinary music-boxes, and to avoid these cumbersome, bulky, and expensive cylinders I have provided the double cylinders with shifting devices for the purpose of shifting them at different times. The cylinders can have any suitable diameter,

and can be made any suitable length, as circumstances may require, and the combs may be composed of a series of sections.

The mechanism is contained in a box in the usual manner.

Having thus fully described my invention, I claim as new and desire to secure by Letters Patent—

1. A music-box provided with two independent pin-cylinders side by side and two independent combs or groups of combs, substantially as herein shown and described. 75

2. The combination, with two pin-cylinders, 80 of an independent shaft for each cylinder, one driving-spring for revolving both shafts, and of an independent comb for each cylinder, substantially as herein shown and described.

3. The combination, with two pin-cylinders, 85 of a comb for each cylinder, two separate shafts for driving the cylinder-shafts, a cog-wheel on each driving-shaft, the cog-wheels engaging with each other, and of a spring for revolving the driving-shafts, substantially as 90 herein shown and described.

4. In a music-box, the combination, with two cylinders, of a shaft in each cylinder, a disk provided with a laterally-projecting pin on one end of each of said shafts, and of wheels 95 having notches for receiving the said pins, substantially as herein shown and described.

5. In a music-box, the combination, with two cylinders, of shafts *E* in the cylinders, the disks *J* on the ends of said shafts, the pins *K* on the said disks *J*, the cog-wheels *R* *R'* on the shafts *P* *P'*, the disks *T* on the cog-wheels, and provided with the notches *U*, and of a spring for revolving the said cog-wheels, substantially as herein shown and described. 100

6. The combination, with the base-plate *A*, of the spring-drum *M*, the cog-wheel *N* on the same, the shafts *P* *P'*, the pinion *O* on the shaft *P'*, and engaging with the cog-wheel *N*, the cog-wheels *R* *R'* on the shafts *P* *P'*, and of pin-cylinders revolved by the shafts *P* *P'*, substantially as herein shown and described. 110

7. In a music-box, the combination, with the base-plate, of two independent pin-cylinders on the same, the two levers *a*, pivoted between the cylinders, a spring acting on the said levers at their inner ends, and of a sliding piece for pressing the outer ends of the said levers from each other, substantially as herein shown and described. 115

8. In a box, the combination, with two cylinders and combs for said cylinders, of a spring for driving the cylinders and of a lever for adjusting both cylinders by one movement, substantially as herein shown and described. 125

9. A base-plate for a music-box provided with two parallel slots for the pin-cylinders, substantially as described.

ALFRED JUNOD.
